US00D598551S

(12) **United States Design Patent**
Miwa et al.

(10) **Patent No.:** **US D598,551 S**
(45) **Date of Patent:** **** Aug. 18, 2009**

(54) **VITAL SIGNS MONITOR**

(75) Inventors: **Yoshihisa Miwa**, Kusatsu (JP); **Hisashi Ito**, Kyoto (JP); **Ayumu Okada**, Aichi (JP); **Atsushi Yasuda**, Komaki (JP); **Tadashi Koike**, Kyoto (JP); **Yukiko Mitsunami**, Otsu (JP); **Takashi Shigeno**, Kawasaki (JP); **Kazuya Andachi**, Kawasaki (JP)

(73) Assignee: **Omron Healthcare Co., Ltd.**, Kyoto (JP)

(**) Term: **14 Years**

(21) Appl. No.: **29/279,953**

(22) Filed: **May 11, 2007**

(30) **Foreign Application Priority Data**

Nov. 14, 2006 (JP) D2006-031245

(51) **LOC (9) Cl.** **24-01**

(52) **U.S. Cl.** **D24/186**

(58) **Field of Classification Search** D24/107, D24/111, 144, 164-165, 168-169, 185-187; 600/301, 481, 483-485, 509, 513, 519, 544; D10/81

(57) **CLAIM**

The ornamental design for a vital signs monitor, as shown.

DESCRIPTION

FIG. 1 is a front perspective view of a vital signs monitor showing our new design;

FIG. 2 is a rear perspective view thereof;

FIG. 3 is a bottom perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof;

FIG. 9 is a left side elevational view thereof; and,

FIG. 10 is a top plan view according to reference arrow 10 of FIG. 8 thereof.

The broken lines shown on the left side of the vital signs monitor shown in FIGS. 9, 5 and 7, are included for the purpose of illustrating a portion of the vital signs monitor that forms no part of the claimed design.

1 Claim, 8 Drawing Sheets
